(57) **CLAIM**

The ornamental design for a multi-position foot rest for foot spa, as shown and described.

DESCRIPTION

FIG. 1 is a front, left elevated perspective view of the multi-position foot rest for foot spa showing my new design; FIG. 2 is a rear, right elevated perspective view thereof; FIG. 3 is a bottom perspective view thereof; FIG. 4 is a left side view thereof;

FIG. 5 is a right side view thereof;

FIG. 6 is a front view thereof;

FIG. 7 is a rear view thereof;

FIG. 8 is a top view thereof;

FIG. 9 is a bottom view thereof;

FIG. 10 is another perspective view thereof;

FIG. 11 is rear, right elevated perspective view of the multi-position foot rest for foot spa, shown in an alternate position;

FIG. 12 is rear, right elevated perspective view of the multi-position foot rest for foot spa, shown in another alternate position;

FIG. 13 is rear, right elevated perspective view of the multi-position foot rest for foot spa, shown in another alternate position;

FIG. 14 is rear, right elevated perspective view of the multi-position foot rest for foot spa, shown in another alternate position;

FIG. 15 is rear, right elevated perspective view of the multi-position foot rest for foot spa, shown in another alternate position;

FIG. 16 is rear, right elevated perspective view of the multi-position foot rest for foot spa, shown in another alternate position;

FIG. 17 is a front, left elevated perspective view of the multi-position foot rest for foot spa, shown in another alternate position; and,

FIG. 18 is a front, left elevated perspective view of the multi-position foot rest for foot spa, shown in another alternate position.

The broken lines in the figures are for the purpose of illustrating portions of the multi-position foot rest for foot spa, which form no part of the claimed design.

The additional broken lines in FIG. 10 are to show environment and form no part of the claimed design.

1 Claim, 14 Drawing Sheets
